CATTLE MARKER

William F. Schacht, Huntington, Ind.

Application October 30, 1941, Serial No. 417,195

11 Claims. (Cl. 40—3)

This invention is a novel improvement in cattle markers which can be readily applied either as a horn chain marker, or neck chain marker, to cattle or live-stock so that farmers, herdsmen or breeders can readily distinguish or identify their cattle or live-stock; the present invention being an improvement upon the markers disclosed in my co-pending applications Serial No. 389,984, filed April 23, 1941; Serial No. 407,968, filed August 22, 1941; and Serial No. 409,734, filed September 5, 1941.

The markers disclosed in Serial No. 389,984 comprise a one-piece marker plate made of flexible material, such as brass or flexible steel, upon which appropriate identification indicia is marked, said plate having a shank which may be single, but is preferably split and the members of the shank then bent back upon themselves to form integral eyes at the upper edge of the plate, a link at one end of the chain being secured in one said eye, the other being left partially open, so that in applying the marker it is only necessary to pass the chain around the neck or horns of the live-stock and to engage a link adjacent the free end of the chain in said open eye, and thereafter close the open eye to lock the ends of the chain around the neck or horns of the animal.

The markers disclosed in Serial Nos. 407,968 and 409,734 are improvements upon those disclosed in Serial No. 389,984 consisting largely in the provision of means at the eyes of the markers for preventing the chain from slipping out of said eyes in event the eyes were not fully closed; also means for preventing the eyes from bending; and means for preventing the eyes from opening, it being found that the animals, when rubbing their horns and heads together, would often catch the chains of the markers in their horns, and moreover the chains would often become caught in fences or the like, with the result that the markers become detached and lost if the strains on the eyes set up by the caught chains was sufficient to cause the eyes to bend or open.

In each of said aforesaid applications the markers were of unitary structure, stamped from sheet material, such as flexible steel or brass, and wastage of metal was considerable. Moreover, at the present time, owing to the large amount of metal assigned to defense orders, such metallic material is difficult to procure; and therefore, I have provided a composite marker plate made from non-metallic non-corrosive material, such as fibre or other material which will

take the stamped imprint of the indicia, same being reinforced with strip steel in such manner that there will be no wastage of metal or fibre, while providing a marker plate which will not tarnish, the steel being utilized to also form the eyes of the marker plate.

One object of my invention, therefore, is to provide a composite marker plate consisting of a fibre or other non-metallic non-corrosive indicia bearing sheet, having riveted across its back a steel strip reinforcing the sheet and preventing warping thereof, said steel strip having its ends projecting beyond the sides of the sheet, which ends are rolled to form the eyes, either single or double, at opposite sides of the marker plate, the outer tips of the rolled eyes seating against the side edges of the sheet to prevent the eyes from opening; or the eyes being provided with raised or offset portions, preferably formed by offsetting the material thereof adjacent their outer ends, the raised or offset projecting inwardly of the eyes adjacent the splits in the eyes and preventing the links of the chain engaged in said eyes from readily slipping or passing therethrough, in event the eyes are not fully closed.

Another object of the invention is to provide a composite chain marker of the above type in which the eyes are preferably but not necessarily offset rearwardly of the plane of the sheet, so that when the marker is used as a horn chain marker, with the plate engaging the forehead of the live-stock, the eyes will maintain the body of the plate spaced from the animal's forehead to provide ventilation thereunder; also to provide a chain having links of relatively greater length than the width of the eyes, whereby sufficient play between the eyes and links is allowed to permit the eyes to move up and down in the links, thus tending to prevent the marker plate from readily turning over on the animal's forehead due to movements of the animal's head; also to provide a marker in which the back of the fibre sheet is provided with a transverse recess receiving the steel reinforcing strip, so that the latter will lie flush with the back of the sheet when the parts are assembled.

Another object is to provide in a composite marker plate of the above type having double eyes at each side of the plate, novel means for preventing the eyes from spreading along the axis of the eyes due to pull on the chain, the use of the double eyes forming a double lock between each end of the chain and the plate.

Another object is to provide a marker of the

above type having novel means for preventing opening of the eyes due to pull on the chain, consisting of offset portions at the bases of the eyes upon which the outer rolled tips of the eyes seat when the metal is rolled to form the eye, said off-set portions being formed by projections, ridges or grooves formed in the material of the eye.

Another object is to provide a composite marker plate particularly adapted for use with young stock, in which the fibre or other indicia bearing sheet is provided with a metal strip at or along its upper edge, which metal serves to reinforce the sheet; and if desired the metal strip may be formed with one or more eye-forming shanks, which eyes would normally be closed; said fibre sheet having slots at opposite sides adapted to be engaged by a strap passing therethrough and around the animal's neck; and when the animal grows older, the strap may be removed and the eye or eyes opened to receive the ends of the chain which passes around the horns or neck of the animal.

Another object is to provide a composite marker plate having a metallic eye in the form of a U-shaped strap embracing the upper edge of the sheet with a ring secured therein, the portions of the strap engaging the sheet being elongated to stiffen the fibre sheet and being secured to the sheet by rivets passing through the ends of the strap and through the sheet.

Another object of the invention is to provide a composite marker having a metallic strip riveted to the upper edge of the sheet and extending above the upper edge of the sheet, the strip having spaced tongues extending from its upper edge which are rolled to form a pair of spaced eyes, one eye being closed on the engaging link of the chain and the other eye left open to receive a link at the opposite end of the chain; and if desired the base of the strip overlying the sheet may extend the full width of the sheet for the purpose of preventing the sheet from warping.

Still another object of the invention is to provide a composite marker of the above type in which the two separate metallic strips may be secured to the upper edge of the fibre sheet, same extending upwardly and outwardly, or vertically, said strips being rolled to form separate eyes for engaging links at the respective ends of the chain.

A still further object of the invention is to provide a composite marker having a single metallic strip extending above its upper edge rolled to form an eye in which a lock ring or split ring is engaged to receive the ends of the chain, said strip if desired extending the full width of the fibre sheet to prevent same from warping.

Other minor objects of the invention will be hereinafter set forth.

I will explain the invention with reference to the accompanying drawings, which illustrate several practical embodiments thereof to enable others to adopt and use the same; and will summarize in the claims, the novel features of construction, and novel combinations of parts, for which protection is desired.

In said drawings:

Fig. 1 is a plan view showing one form of my novel marker plate.

Fig. 2 is a top view thereof showing the chain link locked in one closed eye of the marker plate, and the other eye open to receive the link at the other end of the chain.

Fig. 3 is a top view of a modified marker plate.

Fig. 4 is a top view of a further modified marker plate.

Fig. 5 is a top view of a further modified marker plate.

Fig. 6 is a plan view of a modified marker plate having a pair of eyes at each side, with means for preventing the eyes from opening or separating.

Fig. 7 is a top view of the marker plate shown in Fig. 6.

Fig. 8 is a plan view of a modified marker plate showing a different means for preventing the pairs of eyes from separating.

Fig. 9 is a plan view of a further modified marker plate.

Fig. 10 is a top view of the modified marker plate shown in Fig. 9.

Fig. 11 is a plan view of a further modified form of marker plate.

Fig. 12 is a side view of the marker plate shown in Fig. 11.

Fig. 13 is a plan view of a further modified marker plate.

Fig. 14 is a side elevation of the marker plate shown in Fig. 13.

Fig. 15 is a plan view of a further modified marker plate.

Fig. 16 is a plan view of a still further modified form of marker plate.

Fig. 17 is a side view of the marker plate shown in Fig. 16.

My novel marker shown in Figs. 1 and 2 preferably comprises a sheet 1 stamped from sheet fibre or other non-metallic or non-corrosive material, said sheet 1 bearing the desired indicia which may be engraved, stamped, or otherwise applied thereto; and across the back of sheet 1 is a metallic strip 2 extending beyond the sides of sheet 1 and secured to the sheet by rivets 3 or the like, the back of sheet 1, if desired having a recess therein receiving the said strip 2 so that the strip will be flush with the back of the sheet. The extending portions of the strip 2 are bent or rolled to form eyes 2a, the axes of which are disposed parallel with the plane of sheet 1, each eye being adapted to receive a link at an end of chain 4, which latter is adapted to be passed around the horns or around the neck of the animal, the marker plate securing the ends of the chain 4 together. The axes of the eyes 2a may be disposed in the plane of sheet 1 but if desired same may be offset rearwardly of the sheet, as clearly indicated in Figs. 4 and 5, so that when the marker plate is used as a horn marker, the backs of the eyes 2a will rest upon the forehead of the animal thereby maintaining the sheet 1 spaced from the animal's forehead to allow circulation of air thereunder. Also the links of chain 4 are relatively long with respect to the width of the eyes 2a as indicated in Fig. 1, permitting the eyes of the marker to work up and down in the links of the chain, thereby obviating the tendency of the marker plate to turn over on the forehead due to movements of the head of the animal.

In Fig. 3 the outer tips of the eyes 2a are shown as provided with bulges 2b preferably formed by offsetting the material of the strip 2 but may be formed in any other desired manner, said bulges 2b providing portions on the eyes of substantial size which project inwardly within the rolled eyes, as shown in Fig. 3, adjacent the tips or points of contact of the outer tips with bases of the eyes, the bulged portions 2b serving to prevent the links of chain 4 from readily slipping.

ping out of the eyes in event the eyes should become partially opened, or should not initially be fully closed, the chain links becoming hooked over bulged portions $2b$ when the eyes start to open, or the bulged portions $2b$ serving to present a longer slot through which the links must slip in passing out of a partly opened eye.

As shown in Figs. 1-3, the rolled tips of the eyes $2a$ when closed seat against the sides of the sheet 1 , thus preventing the eyes from readily opening due to strains imposed on opposite ends of the chain 4 , and thus also serving to maintain the links engaged with the eyes in event the eyes should be or become only partially closed.

In practice, the markers would be made up with one eye $2a$ closed tightly to lock the engaged link at one end of the chain 4 therein, while the other eye would be left partially open (as indicated in Figs. 1-3 inclusive) so that in applying the marker to the cattle the farmer or herdsman need only to insert a link adjacent the free end of the chain in said open eye (to provide a chain of the desired length) and to thereafter apply sufficient pressure to close the open eye thereby locking the ends of the chain which passes around the horns or neck of the live-stock to the marker plate, and the sheet 1 of the marker plate which bears the proper identification number or indicia for the respective cow or live-stock, will lie exposed to view slightly spaced from the forehead of the animal when used as a horn marker, or will hang exposed to front view when used as a neck marker since the two eyes tend to prevent the ends of the chain adjacent the marker plate from becoming twisted. As the animal grows, it will become necessary for the farmer or herdsman to pry open one eye $2a$ of the marker and engage a different link of chain 4 in said opened eye, and then again close the said eye to lock said link therein thus permitting the overall length of the chain to be adjusted to correspond with the growth of the live-stock.

In cases where the sides of the sheet 1 do not contact the tips of the closed eyes $2a$ as shown in Figs. 1-3 inclusive, the eyes of the marker would have a tendency to open when the cattle to which the markers are applied lock horns, or graze too near fences, and thus catch the chains 4 in horns or other objects, whereby the strains on the chain tend to pull the eyes open. I therefore provide a novel preventing means, shown in Figs. 4 and 5, in which the strip 2 of the marker plate shown in Fig. 4 is provided with a groove $2c$ extending across the base of the shank portion of each eye into which the outer tip of the eye enters, the lower wall of the groove $2c$ forming a shoulder upon which the outer tip rests and is thus supported to resist ready opening of the closed eye. Preferably the groove $2c$ is formed by offsetting under pressure the material of the strip 2 , but may be otherwise formed in any desired manner. Instead of providing grooves $2c$ shown in Fig. 4, transverse ribs or knobs $2d$ (Fig. 5) may be formed similarly to the grooves, said ribs or knobs $2d$ extending across the shanks of the eyes and forming shoulders upon which the outer tip of the closed eyes seat.

A modified form of marker plate is shown in Figs. 6 and 7 in which the projecting ends of metallic strip 5 , which is of greater width than strip 2 , are provided with spaced tongues $5a$ extending beyond the outer ends thereof, which tongues $5a$ are rolled to form a pair of eyes at each side of sheet 1 , each pair being adapted to engage a link at the end of chain 4 , the pairs of

eyes forming double-locks on the links at each end of the chain. The outer end of each tongue $5a$ may be provided with the bulges $2b$ in the same manner as above described in connection with Figs. 3 to 5 inclusive, and with the grooves $2c$ (Fig. 4) and the ridges or knobs $2d$ (Fig. 5) for the same purpose. Also in this modification the upper and lower edges thereof are bent over to form flanges $5b$ contacting the side edges of the tongues $5a$ when rolled to form eyes, the splits in the eyes being disposed between the flanges $5b$ which serve to prevent the chain links from passing out of the eyes in event the eyes should accidentally become partly open; and the flanges $5b$ also preventing the eyes of each pair from spreading along their common axis to such extent that the eyes would become open.

Instead of using the flanges $5b$ shown in Figs. 6 and 7, straps 6 may be used as shown in Fig. 8, said straps 6 being of length substantially the same as the overall width of each pair of eyes $5a$. One strap 6 and one end of the chain 4 may be initially locked in one of the pairs of eyes $5a$ which are closed tightly over the strap 6 and chain 4 as shown in Fig. 8 to firmly secure same therein at the time the marker is sold. One eye of the other pair would be left open, while the remaining eye is closed on the other strap 6 so that in applying the marker shown in Fig. 8 to the live-stock the farmer or herdsman would merely need to open the last named eye and run the chain 4 around the horns or neck of the animal and engage a link adjacent the free end of the chain in the open pair of eyes and to engage the other strap 6 in the open pair of eyes, and then close said open pair, the links 6 being thus disposed and maintained on the rolled tongues $5a$ adjacent their outer ends, thus preventing the outer ends of the eyes adjacent the splits from separating along the common axes of the pairs of eyes.

In the modification shown in Figs. 9 and 10, the fibre or other non-metallic non-corrosive sheet 1 bearing the indicia is provided adjacent each side with a vertically disposed slot $1x$ of sufficient width to receive a strap (not shown) passed through one slot $1x$ and extending across the back of the sheet 1 and out through the other slot $1x$ and out around the neck of the live-stock, the ends of the strap being secured together by the usual buckle or the like, and said modification being particularly adapted for use on very young live-stock.

Extending from the upper portion of sheet 1 is a metallic strip 7 riveted thereto as at 8 , the strip 7 being rolled to form an eye $7a$, which would normally be closed. However, as the live-stock grows older the strap could be removed from the slot $1x$ and the eye $7a$ opened up and the ends of the chain such as 4 could be inserted in the eye $7a$ which would then be closed, the marker plate with the chain being then usable as above described as a horn or neck marker.

If desired, the portion of the strip 7 underlying the sheet 1 could be of sufficient width to serve as a reinforcement for the sheet 1 to prevent same from warping. Also if desired the strip 7 might be entirely omitted and a steel strip substituted in place thereof extending across the back of the sheet 1 to prevent warpage, or if desired, the marker shown in Figs. 9 and 10 without the metal strip 7 could be made of all fibre if desired.

Where the eye $7a$ is used means similar to bulges $2b$, $2d$ or grooves $2c$ shown in the preced-

ing figures could be used to prevent the eye from readily opening after being closed on the ends of the chain, or if desired, the tip of the tongue $1a$ when closed could abut against the top of the sheet 1 to resist its opening.

In the modification shown in Figs. 11 and 12, the fibre or other sheet 1 bearing the indicia has secured to its upper edge by means of rivets 9 a U-shaped metallic clip 10 , the ends of which overlap the sheet 1 and the clip 10 carrying a ring 11 through which the ends of a strap or chain may be inserted and passed around the neck or horns of the live-stock. Preferably the portion of the sheet metal clip 10 engaging the sheet 1 is of sufficient width to serve as a reinforcement for the sheet 1 to prevent the sheet from warping.

In the modification shown in Figs. 13 and 14, the sheet 1 bearing the indicia has secured to its upper portion a metallic strip 12 having spaced tongues $12a$ extending from its upper edge which are rolled to form a pair of spaced eyes, the outer tips of which are adapted to abut against the upper edge of the sheet 1 .

In marketing the marker shown in this modification, one eye $12a$ of the strip 12 would be closed upon the link at one end, while the other eye would be left open as shown so that in applying the marker to the live-stock the farmer or herdsman needs only to place the chain around the horns or neck of the live-stock and insert a link in the open eye and thereafter close said eye. The tongues $12a$ and strip 12 shown in this modification may, if desired, be provided with any ridges or knobs $2b$ or $2d$ or with the grooves $2c$ shown in preceding figures; also with the flanges $5b$ or links 6 shown in any of the preceding figures and for the same purpose.

Instead of using a strap having a pair of spaced tongues as shown in Fig. 13, the fibre sheet 1 bearing the indicia may be provided at its upper edge with a pair of upwardly and outwardly diverging metallic strips 13 secured by rivets 14 to the sheet 1 , the outer ends of the strips 13 being rolled to form diverging eyes $13a$ adapted to receive the ends of the chain which is passed around the neck or horns of the animal. In this modification the eyes $13a$ and strips 13 may also be provided with the raised ribs or knobs $2b$, $2d$ or the groove $2c$ shown in the preceding figures and for the same purpose.

In Figs. 16 and 17 a further modification is shown in which the fibre sheet 1 bearing the indicia is provided at its upper portion with a strip 15 riveted thereto as at 16 , the outer portion of the strip being rolled to form an eye $15a$, the tip or outer end of which is adapted to seat upon the top edge of the sheet 1 as shown, and if desired the portion of the strip 15 underlying the sheet 1 could extend the full width of the sheet 1 for the purpose of reinforcing same and preventing warpage. Within the eye $15a$ is a lock washer 16 with which one end of the chain could be engaged when the marker is sold and the other end of the link being engaged therewith after the chain has been passed around the neck or horns of the animal. Instead of using a lock ring 16 an ordinary split ring could be used. However, the use of the lock ring has obvious advantages. If desired, the eye $15a$ may be provided with a raised knob $2b$ such as shown in Fig. 3, or if the tip of the eye does not seat upon

the upper edge of the sheet 1 , the strip 15 may be provided with the raised ribs or beads $2d$ or with the groove $2c$ as shown in the preceding figures.

5. I do not limit my invention to the exact forms shown in the drawings, for obviously changes may be made therein within the scope of the claims.

I claim:

10. 1. An animal marker or the like comprising a non-metallic indicia bearing plate, a metallic strip secured to and extending across the back of said plate and extending beyond the sides of said plate, said extending portions being rolled to form eyes; a chain having links at each end adapted to be engaged with the respective eyes; and means for preventing opening of the eyes.

20. 2. In a marker as set forth in claim 1, one said eye being closed and engaging a link at one end of the chain; and the other eye being open and adapted to receive a link adjacent the other end of the chain before closing of said open eye.

25. 3. In a marker as set forth in claim 1, the backs of said eyes being offset rearwardly of the plane of the plate.

40. 4. In a marker as set forth in claim 1, said means comprising raised portions on the strip upon which the outer tips of the rolled eyes rest.

30. 5. In a marker as set forth in claim 1, an offset portion extending inwardly of each eye at the outer end of each shank.

35. 6. An animal marker or the like comprising a non-metallic indicia bearing plate, a metallic strip secured to and extending across the back of said plate and extending beyond the sides of said plate, said extending portions being provided with spaced tongues; said tongues and extending portions being rolled to form eyes; and a chain having links at each end adapted to be engaged with the respective eyes, said tongues forming double eyes locked on the chain links at each side of the plate.

45. 7. In a marker as set forth in claim 6, offset portions extending inwardly of each eye at the outer end of each tongue.

8. In a marker as set forth in claim 6, means for preventing opening of the eyes.

9. In a marker as set forth in claim 6, means for preventing separation of the pairs of eyes at each side of the plate along their common axes.

50. 10. In a marker as set forth in claim 6, means for preventing separation of the pairs of eyes at each side of the plate along their common axes, said means comprising flanges on the sides of the shanks engaging the outer edges of the pairs of rolled tongues adjacent their outer ends.

60. 11. An animal marker or the like, comprising a non-metallic indicia bearing plate; a metallic strip secured to and extending across the back of said plate and extending beyond a side of said plate; a spaced pair of tongues extending from the outer edge of said strip; said strip and tongues being rolled to form spaced eyes having their common axis disposed parallel with the plane of the plate; and an offset portion extending inwardly of each eye at the outer end of each tongue; a shoulder on the base of the shank underlying the outer end of each rolled tongue; and means for preventing the eyes from separating axially.

70. WILLIAM F. SCHACHT.
